UNITED STATES PATENT OFFICE.

ALBERT J. KLUNK, OF ORANGE, CALIFORNIA.

CAMPER'S STOVE.

1,173,145.

Specification of Letters Patent. Patented Feb. 22, 1916.

Application filed August 17, 1914. Serial No. 857,034.

To all whom it may concern:

Be it known that I, ALBERT J. KLUNK, a citizen of the United States, residing at Orange, in the county of Orange and State 5 of California, have invented a new and useful Camper's Stove, of which the following is a specification.

This invention relates to a collapsible stove, and the main object of the invention 10 is to provide a stove which is a single unit, that is, has no separable parts, and which may be folded up into a perfectly flat thin package or may be extended out quickly 15 into expanded position for use. The stove includes a chimney which is formed as a part of the unit and which folds flat with the rest of the stove.

Referring to the drawings: Figure 1 is a view of the under side of the stove showing 20 it folded; Fig. 2 is a plan view of the top of the stove showing it folded; Fig. 3 is a side elevation showing the stove folded; Fig. 4 is a perspective view showing the stove extended for use; Fig. 5 is a rear elevation of the stove.

The stove body comprises a top plate 1 with two side plates 2, each of which is hinged at 3 to the plate 1 and a back plate 4 which is hinged at 5 to the plate 1. The 30 back plate has flanges 6 which project over the side plates 2 and act to steady the side plates 2 and also close the corner preventing a gap.

7 designates the chimney which is shown 35 rectangular in cross section and which consists of side plates 8 and front and rear plates 9 which are hinged together at 10. The front plate 9 of the chimney is hinged at 11 to the top plate 1, and the top plate 1, 40 as clearly shown in Fig. 2, is provided with an opening 12 to communicate with the chimney when the latter is erected and is provided with a flange 13 which projects up slightly from the plate 1 and fits within 45 the bottom of the chimney holding the chimney in expanded position and squarely over the aperture 12 also acting to shut the crack at that point and weaken the draft.

The manner in which the hinge connec- 50 tions have been formed is very essential since it is necessary that no cracks be left in the structure when set up, and since it is desirable to have the structure fold into a very flat form when collapsed. The hinge 55 construction provided fulfills both of these

requirements. The hinge knuckles or sleeves which encircle the hinge pins are integral parts of the walls of the stove and chimney. In reality each wall is a hinge leaf. The knuckles are formed by notching the 60 edges of the walls and bending the portions between the notches to form sleeves, and the sleeves of the joined walls are alternately arranged along the line of juncture so that they will interlock and form with the hinge 65 pin a hinge.

The back plate 4 has a socket 14, and a bolt 15 is slidable in sockets 16 on the chimney 7 and when the chimney is extended as shown in Figs. 4 and 5, the bolt 15 is projected down to engage the socket 14 and thereby lock the chimney firmly in erect position. A pin 17 on the bolt prevents it from being pressed too far down.

To collapse the stove the bolt 15 is slipped 75 up, the chimney is then swung over to free it from the flange 13 and then it is pressed flat as shown in Fig. 2 and laid flatly against the plate 1, then the side plates 2 are folded in flat against the underside of 80 the plate 1 and then the back plate 4 is folded in against the side plates 2 as shown in Fig. 1. The stove is now in a perfectly flat position and in a very convenient condition 85 for carrying in an automobile or pack. Being a unit it is impossible to lose any of the parts.

Considering the entire structure a unit, the stove body and the chimney might well 90 be considered as sub units which when connected as illustrated by the hinge 11 form one unitary structure having no loose parts to become lost or detached. This is highly essential in a camper's stove, because such stoves must often be set up and folded in 95 the dark and must be transported without much care being exercised in the packing thereof. The rough treatment accorded a collapsible portable stove of this nature renders it equally essential that they collapse 100 flatly and leave no projecting parts to be bent, broken or otherwise injured. The chimney 9 collapses into a flat form and folds flatly against the top of the stove body, which in turn collapses into a very 105 compact flat form. If the walls were connected by ordinary leaf hinges, it would not be possible to collapse them so that they would lie flatly against one another, because of the space required by the hinge 110

leaves and knuckles. This is obviated by forming the hinge connections as I have shown and described.

What I claim is:

- 5 1. A camper's stove comprising a top plate, two side plates hinged at their upper edges to the top plate, a back plate hinged at its upper edge to the back edge of the top plate, a chimney comprising a plurality of plates hinged together, one of said plates being hinged at the bottom to said top plate, said top plate having an aperture to communicate with said chimney, a bolt slidable on one of the plates of said chimney, and a 10 socket on the back plate adapted to receive the end of said bolt to lock the chimney in erect position.
- 15 2. A collapsible stove comprising a top plate having side plates and an end plate secured thereto, all foldable thereon to a flat form and a collapsible chimney pivoted to said top plate and both foldable and collapsible thereon to a flat form.
- 20 3. In an article of the character described, the combination with a top plate of a stove, of a smoke pipe collapsible to flat form and pivoted to said top plate, said stove pipe comprising a plurality of side plates all permanently hinged together longitudinally thereof, said pipe being foldable upon said stove and collapsible without detachment of the pipe from the stove and without detachment of any of the pipe sections from each other.
- 25 4. In an article of the character described, the combination with a top plate of a stove, of a smoke pipe collapsible to flat form and pivoted to said top plate, said stove comprising a plurality of side plates all permanently hinged together longitudinally thereof, said pipe being foldable upon said stove and collapsible without detachment of the pipe from the stove and without detachment of any of the pipe sections from each other and means for locking said pipe in upright position.
- 30 5. In an article of the character described, the combination with a top plate of a stove, of a smoke pipe collapsible to flat form and pivoted to said top plate, said stove pipe comprising a plurality of side plates all permanently hinged together longitudinally thereof, said pipe being foldable upon said stove and collapsible without detachment of the pipe from the stove and without detachment of any of the pipe sections from each other and means for locking said pipe in expanded and upright position.
- 35 6. A collapsible stove comprising a top plate, two side plates hinged thereto and foldable inwardly thereon to flat form, an end plate hinged to said top plate and fold-

able inwardly thereon to flat form, a smoke pipe pivoted to said top plate and foldable thereon, said pipe comprising a plurality of sides all permanently hinged together and being collapsible to flat form when folded upon said top plate, without detachment of the pipe from the top plate and without detachment of any of said pipe sections from each other, and co-engaging means for holding said pipe in expanded and upright position.

7. In a camper's stove, the combination with a stove body comprising a plurality of plates hinged to one another and arranged to fold one upon the other inwardly, of a foldable chimney hingedly secured to one of the plates of said stove body and arranged when folded to lie flat upon the stove body, said chimney plates arranged to fold in the same plane with one another, a locking member carried by the chimney, and a co-operating locking member carried by the stove body to lock the chimney in extended position.

8. A camp stove comprising a top plate, side plates hinged along their upper edges to the side edges of the top plate, a back plate hinged at its upper edge to one end edge of the top plate, and flanges on the vertical edges of the back plate, engaging the outer face of the side plate, said side plates to fold against the inner face of the top plate, said back plate to fold upon the side plates, and said flanges to engage the opposed side edges of the top plate when the back plate is in folded position.

9. A camp stove comprising a top plate, side plates hinged to the top plate, and arranged to fold inwardly upon the inner face of the top plate, a back plate hinged to one end edge of the top plate and arranged to fold inwardly upon the side plates, a chimney comprising a plurality of plates hingedly secured to one another along their vertical edges, one of said plates being hinged at its lower edge to the top plate and arranged to fold flat upon and longitudinally of the top plate and either of the plates which is connected with the last named plate being adapted to fold flat against the top plate, all of said chimney plates to lie in the same plane in engagement with one another when folded, said top plate having an opening therein registering with the chimney.

In testimony whereof, I have hereunto set my hand at Los Angeles, California, this 10th day of August, 1914.

ALBERT J. KLUNK.
